LADDER PLATFORM

Edward J. Picone, Arlington, Mass.

Application September 10, 1945, Serial No. 615,400

3 Claims. (Cl. 304—10)

1

This invention relates to ladder platforms of the type which include a platform member adapted to rest on a rung of a ladder and a suspender element which is pivotedly connected to the inner end of the platform member and is adapted to be supported from a rung of the ladder above that on which the platform member rests.

One of the objects of my present invention is to provide improvements in ladder platforms of this type by which the platform member will be held in firm engagement with the rung on which it is supported even though the person using the platform applies his weight to one edge thereof, or to one of the inner corners thereof.

A further object of the invention is to provide improvements in ladder platforms according to which the platform member will still remain supported by the rung on which it rests even though the suspender member becomes accidentally disengaged from the rung by which it is supported.

In ladder platforms of this type the suspender member may have at its upper end a hook portion to hook over the rung by which it is supported and another object of my invention is to provide a novel guard member for the hook portion of the suspender which automatically assumes an operative position closing the hook portion and thus locking the suspender member to the rung by which it is supported, which guard member can be easily shifted into an inoperative position to permit the hook to be disengaged from the rung.

In order to give an understanding of my invention, I have illustrated in the drawings some selected embodiments thereof which will now be described after which the novel features will be pointed out in the appended claims.

In the drawings:

Fig. 1 is a front view of a section of a ladder having my improved ladder platform applied thereto.

Fig. 2 is a section on the line 2—2 Fig. 1.

Fig. 3 is an enlarged section on the line 3—3 Fig. 1.

Fig. 4 is a view similar to Fig. 3 but showing a different embodiment of the invention.

Fig. 5 is a sectional view similar to that shown in Figs. 3 and 4 but showing a still different embodiment of the invention.

Fig. 6 is a top plan view of Fig. 5.

Fig. 7 is a fragmentary view showing the manner in which the platform member is retained on its supporting rung.

Fig. 8 is a fragmentary perspective view showing the improved guard member.

2

In the drawings 1 indicates a ladder provided with the usual rungs 2.

My improved ladder platform comprises a platform member 3 adapted to rest on one of the rungs 2 and a suspender element 4 pivotedly connected to the platform element at the inner end thereof as shown at 13, and having at its upper end a hook portion 14 adapted to be hooked over a rung 2 above that on which the platform member is supported.

The platform member may be made of any suitable material but I will preferably make it from sheet metal. The edges 5 of the platform are shown as being bent downwardly to form 15 strengthening flanges and at the outer end of the platform these strengthening flanges 5 are widened as shown at 6 and each widened portion of each flange is provided with a rung-receiving recess 7 in which the rung 2 is received. Each recess 7 has a horizontal dimension somewhat greater than the diameter of the rung 2 and each widened portion 6 is formed with a throat or opening 8 which leads from the bottom of the widened portion of the flange 6 to the recess 7 25 said throat having a width sufficient to permit the rung 2 to pass therethrough.

Since the recess 7 has a horizontal dimension somewhat greater than the width of the throat 8, the portion 6 of each flange will be provided 30 with two guard portions 9 and 10 which are important factors in holding the platform member on the rung as will be presently described.

The upper wall 11 of the recess 7 inclines upwardly slightly from the outer end of the recess. When the platform is applied to the ladder as shown in Fig. 2, the suspender member 4 will be situated at an inclination and this will apply to the platform a force tending to move it to the left or outwardly. As a result when the platform 35 is installed on the ladder, the rung 2 on which the platform rests will be located in the high portion 12 of the recess 7 as shown in Figs. 2 and 7, and the guard portion 10 of the flange 6 will thus extend around underneath the rung. This is an important feature in providing a secure hold of the platform member on the rung. The suspender element 4 is connected to the central portion of the platform at its inner end, and hence 40 if the person using the platform should apply his weight to one of the inner corners of the platform, there would be a tendency for the platform to tip. With my improvements, however, under such conditions, the guard portion 10 of the flange 50 6 will engage the underside of the rung on which

the platform is supported and will thus prevent any tipping tendency thereof.

If the hook 14 should become accidentally disconnected from the rung 2 of the ladder, the platform member will still remain hung from its rung because although under such circumstances the platform member would swing downwardly, yet the guard portions 9 of the flanges 6 would still retain the platform on the rung and prevent it from dropping off.

The hook portion 14 of the suspender 4 is formed by bending the end portion of the suspender backwardly then upwardly, forwardly and downwardly to form an arcuate shaped hook having a downwardly-opening throat.

The hook 14 has associated therewith a guard member which is constructed to move by gravity from an open-throat position to a closed-throat position, so that when the ladder platform is in use as shown in Fig. 2 the guard member automatically gravitates into its operative closed position.

The guard member is formed with a body portion 16 which is arcuately curved to fit the curvature of the hook 14, and in the construction shown in Figs. 1 to 4, said guard member is mounted on the outside of the hook 14 adjacent the point thereof.

Said guard member 16 is retained in position by means of a guiding loop or strap 17 which is secured to the point portion of the hook on the outside thereof, and which forms between itself and the point of the hook a passageway through which the body of the guard member 16 may slide.

The ends 18 and 19 of the guard member are bent to form stop flanges which by their cooperation with the guide 17 serve to limit the sliding movement of the guard.

In Figs. 2 and 3 the guard is a gravity-actuated element, it being constructed so that when the hook member 14 is applied to a rung 2 the guard member will move by gravity into its lower, or operative, position shown in Fig. 3 in which position the lower end of the guard member extends partially across and therefore partially closes the throat of the hook 14. At this time the upper stop flange 19 of the guard member will rest against the upper side of the guide 17.

When the guard member is in its operative position as shown in Fig. 3, the lower end thereof serves to lock the hook member 14 on to the rung 2 thereby preventing the suspender 4 from being disconnected from the rung.

If, during use, the person using the ladder platform should step on the outer edge of the platform, there would be a tendency to turn the platform counterclockwise in Fig. 2 thereby tending to move the suspender 4 upwardly. Any such movement of the suspender, however, would bring the lower end of the guard member into engagement with the underside of the rung 2 and the pressure thus applied to the guard member would hold it in its operative position and thus prevent the hook portion 14 from being disengaged from the rung.

When it is desired to effect a disengagement of the suspender element from the rung the person using the device may simply apply pressure to the flange 19 of the guard member thus moving it clockwise about the hook 14 and thereby opening the throat of the hook to allow it to be disengaged from the rung.

The guard member shown in Figs. 1, 2, 3, and 8 is a gravity-actuated element, that is, it is constructed so that when the hook member has been

applied to a rung and the guard member has been released, the latter will gravitate from its open to its closed position without any attention on the part of the person using the platform.

If desired, I may employ a spring which operates to assist the gravity-induced movement of the guard member, and in Fig. 4 I have illustrated a construction operating in this way. In the device shown in Fig. 4, the hook portion 14 has a housing 20 mounted thereon in which is located a spring 21 that acts against a thrust pin 22. This thrust pin extends through the wall 23 of the housing and is provided at its inner end with a head 24 with which the spring 21 has engagement. The construction is such that when the guard member 15 is moved into its full, open, or inoperative position, the stop flange 19 of the guard member will engage the pin 22 and force it backwardly thereby compressing the spring 21. When the guard member is released, however, the expansion of the spring 21 will operate through the pin 22 to give the guard member an initial forward movement. The guard member will then continue to move by gravity into its fully operative position shown in full lines Fig. 4.

The advantage of the spring construction shown in Fig. 4 is that the spring will initiate the gravity-induced movement of the guard member thereby insuring that said guard member will always move into its operative position as soon as it is released.

In Figs. 5 and 6 I have illustrated a different embodiment of the invention wherein the guard member which is indicated at 15a is located on the inside of the hook portion 14a of the suspender 4. The guard member has the curved body portion to fit the rung 2 and is provided with two studs 25 which extend through slots 26 with which the hook portion 14 of the suspender is provided, each stud having at its outer end a head 27 overlying the outer face of the hook portion. The heads 27 of the stud are shown as connected by a bar 28 which is acted on by a spring 29, said spring being confined between the bar 28 and a lug 30 rising from the back of the hook portion 14a. This lug 30 is shown as having a curved guide rod 31 secured thereto which extends through the coil spring 29 and the outer end of which extends through an opening 32 with which the bar 28 is provided.

When the guard member 15a is moved into its open or inoperative position as shown by dotted lines Fig. 5, the studs 25 will be carried through the slots 26 and the corresponding backward movement of the bar 28 will compress the spring 29. When the guard member is released, the expansion of the spring 29 will move it into its operative position shown in full lines Figs. 5 and 6 thereby partially closing the open throat of the hook and locking the ladder to the rung.

In the device shown in Figs. 5 and 6 the action of gravity on the guard member 15a will augment the action of the spring in moving said guard member from its open to its closed position.

I claim:

1. Rung-engaging means for a ladder platform comprising an upwardly-extending suspender element by which one end of the platform is supported, the upper end portion of said suspender element being bent backwardly then upwardly, forwardly and downwardly to form an arcuate rung-engaging hook portion having a downwardly-opening throat, and a guard member having a body portion which is also arcuate-shaped and which conforms in shape to that of the hook portion, said guard member being slidably by

gravity over the free end portion of the hook from an open-hook position towards the suspender element to close the throat.

2. Rung-engaging means for a ladder platform comprising an upwardly-extending suspender element having its upper end portion bent backwardly then upwardly, forwardly and downwardly to form an arcuate rung-engaging hook having a downwardly opening throat, a guard member having a body portion which is also arcuate-shaped and which conforms in shape to that of the hook, said guard member being mounted on the outside of the hook and slideable by gravity over the free end portion of the hook from an open-hook position towards the suspender element to close said throat, and a guide member on the exterior of the hook adjacent to its point but spaced therefrom to form a passage through which the guard slides in opening and closing the throat of the hook, the ends of the guard member being bent to provide stop portions to limit the opening and closing movement thereof.

3. Rung-engaging means for a ladder platform comprising an upwardly-extending suspender element by which one end of the platform is supported, the upper end portion of said suspender element being bent backwardly then up-

wardly, forwardly and downwardly to form an arcuate rung-engaging hook portion having a downwardly-opening throat, a guard member having a body portion which is also arcuate-shaped and which conforms in shape to that of the hook portion, said guard member being slideable by gravity over the free end portion of the hook from an open-hook position towards the suspender element to close the throat, and a spring acting on the guard member when in open position and tending to assist its gravity-actuated closing movement.
